UNITED STATES PATENT OFFICE.

PAUL LIPPERT AND THOMAS E. RICHARDS, JR., OF CHICAGO, ILLINOIS.

TRANSPORTATION APPARATUS AND METHOD FOR USE IN DRIVING TUNNELS.

1,404,036.

Specification of Letters Patent. Patented Jan. 17, 1922.

Application filed July 6, 1920. Serial No. 394,311.

To all whom it may concern:

Be it known that we, PAUL LIPPERT and THOMAS E. RICHARDS, Jr., citizens of the United States, and residents of Chicago, county of Cook, and State of Illinois, have invented certain new and useful Improvements in Transportation Apparatus and Methods for Use in Driving Tunnels, of which the following is a specification.

10 Our invention relates generally to transportation apparatus and methods for use in driving tunnels. It has certain aspects which relate particularly to use with tunnels that are to be provided with masonry, concrete or

15 other lining.

In tunnel work one of the most difficult problems to be solved is that of haulage. This is especially so in tunnels where the material must be hauled long distances. A satisfactory haulage system for underground work must embody the elements of safety, economy in installation and maintenance, economy in haulage, and must be one with which it shall be possible rapidly to dispose 25 of the materials as the tunnel progresses. Several forms of haulage systems have been proposed and are in use with more or less success.

One system of underground haulage employs a locomotive operated by an internal combustion engine and while this has the advantage of being an automotive device requiring no extraneous source of power it is extremely objectionable due to the discharge 30 of gases therefrom, which aggravates the already difficult problem of maintaining a satisfactory air condition in the tunnel. For this and other reasons such haulage systems have met with little favor.

40 Another form of locomotive proposed and used to some extent is a locomotive utilizing storage batteries as a source of power. Locomotives of this kind while having freedom of movement are initially expensive, are very heavy, and the haulage cost is relatively high. Again in a storage battery best adapted for heavy duty work such as an Edison battery it is dangerous to charge such batteries underground due to the discharge of 45 hydrogen at that time. When storage battery locomotives are used in tunnel work it becomes necessary to erect a charging station above the ground. This results in adding materially to the work involved since it requires the elevation and lowering of many

heavy batteries. For this and other reasons locomotives of this type are little used.

A third type of haulage is that employing an electric locomotive securing its power from a trolley wire. This system of haulage 50 is used to a very great extent since it can be installed quickly and at relatively low cost. The trolley system of haulage, however, involves a number of objections which seriously impair its adaptability to tunnel 55 work. Particularly is this so when the tunnels are to be provided with concrete, masonry or other lining. In tunnel work where the lining is to be provided it is common practice to drive the tunnel for a distance of 60 one or two thousand feet before commencing work upon the lining or concrete work. Long before this distance is reached, however, it is desirable to provide power haulage means in order to dispose of the excavated 65 material rapidly and economically. To this end, a track system is installed and a trolley wire provided. The trolley wire is initially suspended from the tunnel roof. When a concrete form of lining is provided concrete 70 mixing apparatus of one form or another follows up the drifting work at some predetermined distance in the rear. Such concrete mixing and applying apparatus is of 75 such size as to require all of the head room which it is possible to secure in the tunnel and in fact in some instances special grooves or excavations must be made in the roof to make room for parts of the applying or mixing apparatus. For this reason it becomes 80 necessary to remove the depending trolley wire to permit or accommodate the concrete mixing and applying apparatus. Thereafter, the trolley wire system is again 85 installed which installation remains in place only until the steel forms which it is customary to use in connection with concrete 90 work advance. It then becomes necessary to remove the trolley wire to permit forward movement of the concrete forms. The trolley wire is again replaced behind the concrete forms depending from the now lined roof of the tunnel where it remains until finally removed. It will thus be seen that 95 trolley system requires the placement and removal of the wire several separate and distinct times in the course of the tunnel construction work. This is a slow, laborious and expensive operation. Another serious 100 objection to the trolley wire system lies in 105 110

the fact that it is not possible to work very close to the point where the tunnel is being drifted for it is usually necessary to blast to a considerable extent and in the blasting 5 operation the material has a tendency to fly toward the upper part of the tunnel where the trolley wire hangs. This is occasioned by the best practice of blasting in which a table is formed by the lower part of the ma- 10 terial to be excavated which table serves to direct the upward blasted material toward the ceiling of the tunnel. If the trolley wire is carried very close to the blasting point, it would be torn down. It is, therefore, the 15 common practice to stop the trolley wire a considerable distance behind the blasting point. This creates another problem, i. e. that of moving the material from the point where the trolley wire stops to the blasting 20 point and to this end a number of expedients have been proposed which are open to objection upon one or more grounds.

It is an object of our invention to provide a transportation apparatus and method 25 for use in driving tunnels which shall be safe, simple, of relatively low cost, and which can be maintained in working order easily and at little expense.

Another object of our invention is to provide an apparatus and method of the above 30 character that can be employed relatively close to the blasting point, that is capable of use where the tunnel is to be lined, without the necessity of removal of the electrical 35 conductor at any time; and which shall be adaptable for use in standard tunnel driving practise.

Again, it is an object of our invention to provide an apparatus and method whereby 40 power haulage can be maintained through concrete or other lining forms and which shall at the same time permit the advancing of the forms from time to time without the necessity of making and breaking the 45 electrical connection as the tunnel forms move forward.

Our invention consists generally in the form, arrangement, construction and co-operation of the parts and in the steps, acts, 50 and stated sequence thereof whereby the above named objects, together with others that will appear hereinafter are attained.

Our invention will be more readily understood by reference to the accompanying 55 drawings which illustrate what we consider at the present time to be the best embodiment thereof.

In said drawings:

Fig. 1 is a cross section through a tunnel 60 which is being drifted and which is partly lined.

Fig. 2 is a cross section through a tunnel showing the concrete form in place and the tunnel lined with concrete.

Fig. 3, is a horizontal view through a

part of the tunnel and through the concrete form being viewed substantially along the line 3—3 of Fig. 2.

Fig. 4, is a detail sectional view substantially on the line 4—4 of Fig. 3.

Fig. 5 is a detail view showing means of joining sections of the electrical conductor.

Fig. 6 is a sectional view substantially on the line 6—6 of Fig. 5.

Fig. 7, is a view in elevation of a transmission pole used for conducting current to the locomotive.

Fig. 8 is a sectional view substantially on the line 8—8 of Fig. 7.

Fig. 9, is a detail view showing how the conductor enters the locomotive.

Fig. 10 is a plan view of what we term a carriage shoe showing it mounted upon a conductor rail.

Fig. 11 is an elevation of the carriage shoe 85 of Fig. 10.

Fig. 12, is a sectional view substantially on the line 12—12 of Fig. 10.

Fig. 13 is a plan assembly view showing conductor rail, carriage shoe, and transmission pole; and

Fig. 14, is a view substantially on the line 14—14 of Fig. 13.

The tunnel 2, illustrated in the drawings is formed with an arched ceiling 3, vertical 95 side walls 4 and 5 and substantially horizontal bottom or floor 6. This tunnel, it should be understood, is by way of illustration and not by way of limitation. Inasmuch as the invention is of especial importance in connection with tunnels that are to be lined with masonry, concrete and the like, we shall describe the formation of the tunnel with such lining. As the tunnel is drifted portions of the lining are provided along the side walls 4 and 5, as well shown in Fig. 1 where these portions bear the numerals 7 and 8. As a matter of convenience in description, we shall refer to these wall portions 7 and 8 as footing walls. 100 These footing walls are always initially provided for a lined tunnel and the upper faces 9 and 10, respectively, of these walls are formed to grade. The inner faces 11 and 12, respectively, are formed the proper distance apart to give the tunnel the width desired and these also serve as guides for the placing of the form that is used in applying the concrete lining to the remainder 110 of the tunnel. It should be understood that 105 these footing walls are always formed prior to the formation of the complete lining but the work performed thereon is in no sense lost because these footing walls form a part of the lining. In order that a bond may be 120 better formed between the remaining part of the lining and these sub walls it is customary to provide the upper faces 9 and 10 with grooves or depressions 13 and 14, respectively,

We take advantage of these footing walls to provide grooves or housings for an electrical conductor which is to supply current to the haulage locomotive that is to operate 5 over the tracks 15 and 16, respectively. Inasmuch as the electrical conductors on each side of the tunnel are alike a description of one will suffice for both. The electrical conductor may assume various forms, but, 10 as here shown, it takes the form of a T-rail, 17, which is suitably supported by means of insulators 18. The T-rail is mounted in a groove or recess 19 that we form for this purpose in the footing wall. 15 The recess or groove 19 is preferably formed of a depth such that the electrical conductor does not project beyond the inner face of the wall. This arrangement not only removes danger of accidental contact by workmen in the tunnel, but, what is also of great 20 importance, prevents the flying fragments, during the blasting operation, from injuring the conductor. Because of this pocketed arrangement of the conductor in the 25 footing wall the conductor can be safely carried to a point very close to the blasting point. It becomes possible therefore to provide haulage directly to the point where the material is found, thus obviating the necessity 30 of makeshifts heretofore provided where the trolley system is used.

The conventional method of transferring current from the conductor to the locomotive has certain inherent objections especially 35 for tunnel work and we have provided novel apparatus which greatly simplifies the hauling problem and which insures the constant safe and efficient functioning thereof. We might here state that at times it is necessary 40 for the locomotive to leave the main track and enter a switch track as when passing through the concrete form. The description of the concrete form, switch, and associated apparatus which we have provided to this 45 end will be described hereafter and we only mention it at this time to indicate that the peculiar requirements of tunnel construction have influenced the design of nearly all of the parts. Also in tunnel work there are 50 many instances when the electrical connection must be broken between the conductor and the locomotive such for example when crossing intersections, passing around switches, etc.

55 On the electrical conductor we mount what we shall hereinafter term a "carriage shoe." This carriage shoe comprises a contact block 20 which rests upon the head of the conductor rail 17 and which has an up-standing shank portion 21, which is held 60 in position by the frame or block portion 22. The frame or block portion 22 is held in position and fixed to the rail by means of a plurality of roller wheels 23 that are 65 carried upon vertical bolts or pivots 24.

Thus it will be observed that the carriage shoe will maintain itself properly in place upon the conductor rail and at the same time may be moved along the rail as desired. Also of importance is the fact that good 70 electrical contact is constantly maintained by the construction provided. Attached to the frame or block 22 at each end we provide hook blocks 25. The construction of these hook blocks are alike so a description 75 of one will serve for both. The hook blocks are provided with spaced jaw portions 26 and 27 which define a recess 28. A transmission pin shortly to be described is adapted to be inserted and wedged into place in 80 either of these hook blocks 25.

There are two other main elements that are utilized in transmitting current from the carriage shoe to the locomotive and they are what we term the operating head 85 and the transmission pole. The operating head carries a transmission pin 29 from which extends, near one end, a shank portion 30 which terminates in a latch portion 31. The transmission pin 29 is securely 90 bolted to an insulating handle block 32 and to the handle block 32 is suitably secured a handle 33. The handle is thoroughly insulated from the transmission pin 29. The transmission pin 29 passes through a disk 95 34 which disk has a square hole therein and the transmission pin at this point being square the disk is prevented from turning. The disk 34 is held in position by means of lock stud pins 35 and the entire assembly is 100 held securely together by means of the nut 36. Fitted to revolve freely about the transmission pin is a yoke block 37 which has two yoke cap screws 38. By means of these yoke cap screws the yoke 39 and yoke flange 105 40 are attached to the yoke block. The yoke block, being free to revolve about the transmission pin, and the yoke being free to revolve about the yoke cap screws, in a plane normal to the plane of motion of the yoke 110 block, constitutes a universal joint and allows motion in any plane.

Bolted to the yoke flange by means of pole flange 41 is the transmission pole 42. The transmission pole is preferably made of an 115 insulated or nonconducting material and of such length as may be required by operating conditions. Attached to the yoke flange, pole flange, or pivot is a cable lug 43. This lug has a conducting cable 44 attached to 120 it in the usual method as by soldering or any other desired way. The pole flange may in some instances be insulated from the yoke flange in which event the cable lug will be fastened to the yoke flange only.

The operating head is usually placed within 125 convenient reach of the operator and can be connected and disconnected to the carriage shoe by means of a turning motion of the handle. The entire apparatus, namely 130

carriage shoe, frame block, hook blocks, transmission pin, yoke block and cable lug are all in good electrical contact and transmit to the cable 44 the necessary electrical current with small loss of voltage. Under most operating conditions the pole flange will also be in good electrical contact with all of the above mentioned parts. The pole 42 is attached to a pole connecting the block 10 45 which is carried in or by the links 46 and 47. The links 46 and 47 are pivotally united as by means of pivot pins 48 and 49 with similar links 50 and 51 which in turn support similar parts carrying the rear end 42' of 15 the pole.

The links 46, 47, 50 and 51 joining the pole portions 42 and 42' carry, on the pivots 48 and 49 helical springs 52 and 53 which tend to move the pole portions 42 and 42' toward 20 each other. At the same time the construction is such as to permit distension as required in operation. The links have such lengths and range of motion as are required by any operating condition.

Attached to the pole portion 42' is the pole 25 coupling 54 and pole fork 55. The pole fork is of size to suit operating conditions or peculiar features of the locomotive to which the entire transmission pole will be connected, and is attached to the pole bearing 30 56 by two pole cap screws 57. This fork is free to turn about the cap screws 57. The pole bearing 56 is held in position relative to the pole connecting pin 58 by two hollow set 35 screws 59. These screws are fitted into a slot cut in the pole connecting pin entirely around its circumference. The hollow cap screws are so fitted in this slot to allow the pole bearing to turn about the pole connecting pin.

Referring again to the pole fork and pole bearing, it will be seen that the plane of motion of the fork is normal to the plane of motion of the pole bearing giving a universal joint and allowing motion in any 45 plane. The pole connecting pin 58 is connected to the apparatus which is to be driven by means of the pole connecting pin flange 60 in any suitable manner.

The cable 44 passes through the pole 42 between links, through pole portion 42', through pole coupling 54 and through pole connecting pin 58 and into the machine or locomotive to be driven from whence it is 55 led, in any convenient manner, to the control apparatus of the machine.

The cable being insulated there will be no current flow through the pole, links, fork or pin.

Again it may be stated that the entire apparatus, namely, carriage shoe, operating head and transmission pole are made of sizes and strengths suitable to any operating condition. The cable is likewise proportioned

to have a safe carrying capacity of electrical 65 current for load placed upon it.

The motion of the carriage shoe along the rail or conductor is guided and fixed thereon by means of the roller wheels necessitating accurate alignment for satisfactory operation. This alignment is attained by a dowel bond and tie plate best shown in Figs. 5 and 6 of the drawing.

In the rail or conductor a hole 62 is drilled and tapped to a depth equal to the length 75 of the dowel bond 63. The dowel bond is slotted on opposite sides as indicated at 67 to receive the squared ends of the dowel keys 68 that are screwed into the dowel bond nut 64 and can be slipped along this slot. The 80 dowel bond nut 64 has a section exactly of same dimensions as head and web of the rail or conductor to which the dowel and nut are connected. The tie plates 65 are attached by bolts 66 to the rail flanges.

In use the dowel bond is screwed by means of the dowel bond nut into the tapped hole of the fixed rail until the exposed end of the dowel bond is flush with the face of the dowel bond nut. The rail or conductor to be placed is then butted tightly to the dowel bond nut. The tie plate is then connected to both rails or conductors bringing the two rails or conductors into perfect alignment. The dowel bond nut is now turned in a reverse manner to unscrew the dowel bond. This motion backs the dowel bond out until the replaced or new rail or conductor has received into it exactly the same length of dowel bond as remains in the fixed rail or conductor.

The limiting of the dowel bond travel is attained by cutting the slots 67 of a length from one end only equal to one-half of the total length of the dowel bond plus the 105 thickness of the dowel bond nut. When this limit of travel has been attained the dowel bond nut is firmly forced against the replaced or new rail or conductor and brought into exact coincidence with the rail head making a continuous and unbroken rail head throughout the length of the conductor.

The stem can be of any length. In fact, the dowel bond nut 64 can be a full rail or conductor section, that is, head, web and flange are exact counterparts of the rail or conductor to which it is attached.

The dowel bond being made a highly efficient conductor of electrical current not only gives alignment but serves as an excellent 110 electrical bond reducing electrical losses to a minimum. The tie plates also assist materially in reducing electrical losses and maintaining alignment.

There remains yet to be described the construction of the switch by means of which 125 passage may be had through the concrete form.

The concrete form 70 is of a common and well known construction and is suitably braced by horizontal and vertical members 71, 72, and 73. By means of the connections 5 74 between the wall of the form and the brace 71 and by means of the turn buckles 75, extending between the vertical braces and the side walls, the walls of the form can be reduced in size to permit forward movement 10 of the form, which is necessary as the work progresses. To facilitate this forward movement the form structure is mounted upon wheels 76 which rest upon rails 77 provided for that purpose. It will be observed 15 that the form structure would interfere with passage of the train along the rails 16 and hence a switch or turnout 16' is provided so that the locomotive and train may leave the track 16 and pass through the form and 20 thereafter return to the main haulage track. We provide means for insuring the operation of the locomotive through the form at all times. To this end we have provided an electrical conductor as shown at 78 which 25 follows the form of the switch track 16'. This conductor 78 is similar to the main conductor that is mounted in the recess 19 and at its ends comes close to but does not touch the main conductor. For the purpose 30 of bringing current to the conductor 78 we provide, in this instance, a carriage 83 which is mounted upon the main conductor 17 which may in construction be like the carriage shoe heretofore described. In any 35 event it has the same characteristics, i. e. is slidable along the main conductor. By means of a cable or bond 80 which is joined to the conductor 78 current is transmitted to and the conductor 78 is energized. As the 40 form moves forward, the conductor 78 moves therewith and this drags the carriage 79 so that at all times we are assured of proper transmission of current to the conductor rails 78 without the necessity of making 45 and breaking connections from time to time. A portion of the conductor rail 78 extends beyond the ends of the form and in order to support these end portions we have provided at one end a plurality of hangers 50 81. These hangers have a portion 82 which fits into the groove 14 of the footing wall and which serves to hold the hangers firmly in place. At the same time, the hangers can be readily removed as may be necessary 55 from time to time. The other end of the conductor rail, i. e. where the lining has been completed is supported from the form by means of a brace 81'. (See Fig. 3.) On the conductor 78 we also provide a carriage 60 shoe, as indicated at 83 which in construction may be like the carriage shoes heretofore described with reference to the main conductor.

By this construction the locomotive can

be operated through the form without 65 danger of going "dead" while in the form.

Method of operation.

The carriage shoe, as before stated, has two hook blocks, one at each end arranged to 70 receive the transmission pin and its attachments. To make connection with the carriage shoe, the operator grasps the handle, sets the transmission pin in a hook block and turns the handle in the direction toward 75 the contact shoe shank and thereby firmly wedges the transmission pin in position. The operator can now drive the locomotive because he has a full and complete electrical circuit from the main conductor rail and 80 grounded rails or tracks. The transmission pole either pulls or pushes the carriage shoe. By means of the universal joint at the operating head and connecting pin and also by means of the connecting links which are 85 restrained by the helical springs thereon, the variations between the conductor rail and the haulage tracks are easily compensated for without shock or strain to any of the parts. This is important in tunnel and 90 similar work because considerable variation both in alignment and grade of the haulage tracks are frequently met with. Because of the comparatively great range of motion 95 both in alignment and grade our transmission pole eliminates the necessity of any very accurate alignment and grade between the conductor rail and the haulage tracks such as is required in all other third rail systems.

After connection is made with the carriage shoe, the locomotive may be started and when underway continues along the track until stopped either for cross-overs, switches, or the end of the trip. Usually the operator will stop his train a fixed distance 100 from the cross-overs, switches, etc. Upon receiving his signal to go ahead he will start his train, building up speed, and when within fifteen or twenty feet from the intersection, cross-over, switch, or the like, by a 105 reverse turn of the handle will disconnect the transmission pin from the carriage shoe and coast across the cross-over, intersection, etc. The carriage shoes are dropped by incoming and outgoing trains usually within 110 fifteen or twenty feet of the side of the cross-overs or intersections. After crossing the intersection the operator allows the transmission pin to slide along the rail head holding it in this position by means of the 115 handle until the carriage shoe is met at which time he places the transmission pin into the hook block and there wedges it in place in the manner before stated. Because of the ease and accessibility of the parts 120 any proficient operator can drop or pick up, i. e. connect and detach the transmission pin 125 while in motion thus eliminating the neces-

sity of stopping the train for that purpose.

In order that the locomotive and its cars may pass through the form which is provided with a crawl switch and in which the available space is small it is necessary that the locomotive move very slowly—that is to say, it is not feasible to coast through the form. For passage through the form the locomotive drops the carriage shoe on the main conductor, picks up the carriage shoe on the conductor carried by the form, passes through the form dropping the form carriage shoe just before passing on to the main tracks and there picking up the carriage shoe on the main track for the continuation of the trip.

It is possible with our construction for locomotives operating in both directions to use the same conductor rail. This is accomplished by the respective locomotives dropping the carriage shoes as they approach each other and thereafter picking up that shoe which was dropped by the other locomotive.

The many advantageous features of our invention will be understood by those skilled in this art without further comment, but, inasmuch as this disclosure will readily suggest to such persons various modifications whereby the substantial objects and purposes of our invention can be attained we do not wish to limit ourselves to the specific construction herein shown and described nor to the precise steps or stated sequence of the method of operation, except only as may be necessary by limitations in the hereunto appended claims.

We claim:

- 40 1. In a tunnel haulage construction for tunnels that are to be lined, a footing wall that is to form part of the lining, a groove in the side thereof and an electrical conductor mounted in said groove.
- 45 2. A method of providing haulage for tunnels that are to be lined that consists in forming a footing wall with a recess therein and in mounting an electrical conductor in said recess before completing the tunnel.

3. In a tunnel haulage construction, a footing wall that is to form part of the lining, a groove in the side thereof and a rail electrical conductor in said groove.

4. A method of providing haulage for tunnels that are to be lined with concrete that consists in providing a concrete form, in providing an electrical conductor longitudinally of the tunnel and beyond the ends of the form, in providing said form with an electrical conductor and in maintaining constant electrical connection between said first mentioned conductor and the conductor carried by the concrete form.

5. A tunnel haulage and lining apparatus embodying therein a portable concrete form, an electrical conductor extending longitudinally of the tunnel and beyond the ends of the form, an electrical conductor carried by the concrete form, a shoe carriage free to move on the first mentioned conductor, and an electrical connection between said shoe carriage and the electrical conductor carried by the form.

6. A tunnel haulage and lining apparatus embodying therein a portable concrete form, an electrical conductor extending longitudinally of the tunnel and beyond the ends of the form, an electrical conductor carried by the concrete form, and shoe carriages mounted upon the respective conductors and free to move independently thereon.

7. A tunnel haulage and lining apparatus embodying therein a portable concrete form, an electrical conductor extending longitudinally of the tunnel and beyond the ends of the form, an electrical conductor carried by the concrete form, a shoe carriage free to move on the conductor carried by the concrete form, and shoe carriages upon the tunnel conductor and disposed beyond the respective ends of the concrete form.

In testimony whereof, we have hereunto set our hands, this 2nd day of July, A. D. 1920.

PAUL LIPPERT.
THOMAS E. RICHARDS, JR.
